UNITED STATES PATENT OFFICE.

GEORGE N. KENYON, OF NARRAGANSETT PIER, RHODE ISLAND.

DUMPING-BARGE.

SPECIFICATION forming part of Letters Patent No. 394,073, dated December 4, 1888.

Application filed January 10, 1887. Serial No. 223,978. (No model.)

To all whom it may concern:

Be it known that I, GEORGE N. KENYON, a citizen of the United States, and a resident of Narragansett Pier, in the county of Washington and State of Rhode Island, have invented a new and useful Improvement in Means for Unloading Barges, of which the following is a specification.

Heretofore in unloading barges laden with coal, grain, &c., it has been the practice to raise the said material to the wharf in buckets operated by means of a stationary steam-engine located upon the wharf; but on account of the vast amount of such freight to be transported and unloaded it is highly desirable to secure a more rapid and economical means for unloading such materials from the barge in which it is shipped; and my invention consists in the improved construction of the barge, whereby the same is adapted to unload its cargo from an inclined railway, as hereinafter fully set forth.

Figure 1 is a longitudinal section of the barge, showing the screws for raising the inner portion of the supplemental decks. Fig. 2 is a transverse section of the same. Fig. 3 is an enlarged detail transverse section. Fig. 4 is a detail view showing the screw and pivoted nut which serve to support the inner portion of the supplemental deck.

The movable supplemental decks H H of the barge rest at their outer edges upon the main deck I, and are supported at their inner portions by means of the duplicate series of screws J J J and the pivotally-held nuts K K K, which are secured to the under side of the supplemental decks by means of the bearing pieces or straps L L, the nuts K being provided at their opposite sides with the pintles r r. The screws J are held at their lower ends in a step, M, and are each provided with a worm-gear, M', which engages with the worm N upon the shaft O, which extends from end to end of the barge and which is to be supported in suitable bearings. Movement of rotation is imparted to the shaft O from either end of the barge by means of the hand-wheels or capstans P, which are operatively connected to the shaft O by means of bevel-gears T, thus causing the supplemental decks H H to be raised or lowered simultaneously, upon the proper movement of the hand-wheel, the

screws of one longitudinal series being provided with a right-hand thread and the screws of the opposite series with a left-hand thread, 55 in order that with the same operating-worm N the decks H H may be moved simultaneously in the same direction.

The screws J J are so connected to the step M, by means of a rounded end, or otherwise, 60 as to allow the required lateral movement of their upper ends with the angular movement of the decks H H. Upon the screws J J are loosely placed the covers Q, which serve to prevent the ingress of water through the slot-openings q in the main-deck I into the hold U. A hinged or yielding cover, V, is also arranged longitudinally of the supplemental decks H H, which serve to cover the variable opening between the inner edges of the said 70 decks, and the said cover V may be provided with slots s, adapted to receive the projecting ends of the screws J J.

In loading the barge, the decks H H may be brought by means of the screws to the level 75 of the main deck I, and when it is desired to dump the load which has been placed upon supplemental decks the said decks are to be elevated to the proper inclined position by the required movement of the screws, until 80 the load placed upon the deck will slide by gravity into the receiving-bin.

I claim as my invention—

1. The barge provided with an adjustable supplemental deck formed in two opposite 85 parts, which have a pivot or fulcrum upon the main-deck at each side of the barge, in combination with the screws and nuts for raising or lowering the inner portion of the supplemental deck, and the cover which serves to 90 bridge the central opening between the opposite parts of the supplemental deck when in its raised and inclined condition, substantially as described.

2. The barge provided with an adjustable 95 supplemental deck formed in two opposite parts, which have a pivot or fulcrum upon the main-deck at each side of the barge, in combination with the duplicate series of screws for raising or lowering the inner portion of 100 the supplemental deck, the centrally-arranged shaft for connectedly turning the series of screws, the series of worms secured to the central shaft, and the series of worm-gears se-

cured to the duplicate series of screws, substantially as and for the purpose specified.

3. The barge provided with a supplemental deck formed in two opposite parts, which have 5 a pivot or fulcrum upon the main-deck at each side of the barge, in combination with means for varying the inclination of the opposite

parts of the supplemental deck, and the cover for the open space between the inner edges of the same, substantially as described.

GEORGE N. KENYON.
